Specification of Letters Patent. Patented Apr. 25, 1916.

Application filed November 6, 1915. Serial No. 59,949.

To all whom it may concern:-

Be it known that I, MARCUS T. GOLDSMITH, a citizen of the United States, and a resident of Newark, in the county of Essex 5 and State of New Jersey, have invented a new and Improved Clip, of which the following is a full, clear, and exact description.

The object of the invention is to provide a new and improved clip for use on fountain pens, clinical pocket thermometers and other articles intended to be carried in the pocket and arranged to permit a retailer or other person to conveniently and quickly attach the clip to the article with a view 15 to securely hold the article in position in the user's pocket.

In order to accomplish the desired result use is made of a tubular shell provided with a transversely extending slit and a clip having a resilient shank, a toe extending integrally and upwardly from the base end of the shank and adapted to rest exteriorly on the shell adjacent the said slit, a lug extending integrally from the base end of the 25 shank in a rearward direction and passing through said slit, the lug having an aperture extending within the shell, and a wedge passing through the said lug aperture and fitting against the interior surface of the 30 shell.

A practical embodiment of the invention is represented in the accompanying drawings forming a part of this specification, in which similar characters of reference indicate corresponding parts in all the views.

Figure 1 is a perspective view of the clip as applied to the cap of a fountain pen; Fig. 2 is a side elevation of the clip as applied to the cap of a fountain pen, the cap 40 being shown in section on the line 2—2 of Fig. 1; Fig. 3 is a rear elevation of the clip as applied to the cap of a fountain pen, the cap being shown in section on the line 3—3 of Fig. 2; Fig. 4 is a perspective view of the clip; Fig. 5 is a similar view of the key; and Fig. 6 is an enlarged sectional view of the clip as applied, the section being on the line 6—6 of Fig. 3.

In Figs. 1, 2 and 3 is shown a clip 10 applied to the tubular cap 11 of a fountain pen but I do not limit myself to this particular use of the clip as the clip may be applied to tubular members of other articles such as clinical pocket thermometers and the like. 55 The clip 10 comprises a resilient finger or a shank 12 terminating at its base in a rear-

wardly extending lug 13, and a toe 14 preferably struck up from the lug 13 extends in an upward direction to rest against the exterior surface of the tubular member 11. 60 The tubular member 11 is provided intermediate its ends with a transverse slit 16 into which fits snugly the lug 13, the latter being of sufficient depth to project a distance within the tubular member 11, as plainly indicated in Fig. 2, to permit of driving a wedge 17 partly through the aperture 15, the wedge 65 extending lengthwise of the tubular member 11 and resting against the inner surface thereof. 70

The tapering sides of the wedge 17 engage the side wall of the aperture 15 to hold the wedge against accidental displacement. It will be noticed that the toe 14 rests on the outer face of the tubular member 11, the 75 rear face of the wedge 17 engages the rear wall of the aperture 15 and the front face of the wedge fits against the inner surface of the tubular member 11 so that the clip 10 is securely locked in place. In practice, the 80 clip can be readily applied to a tubular member as it is only necessary to provide the tubular member with the slit 16 and then fasten the clip in place, as shown and described. Most of the tubular members now 85 generally in use are made of hard rubber and the proper sized slit 16 can be readily formed therein by the use of a correspondingly shaped and heated tube. The wedge 17 is preferably provided near its base with 90 an aperture 18 for the insertion of a suitable hook or other tool for withdrawing the wedge 17 in case it is desired to remove the clip 10 from the tubular member 11. 95

The clip shown and described is very simple in construction and it can be readily fastened in place on the tubular member, and by curving the shank or finger 12 directly outwardly from the lug 13 it is possible to engage the flap of a pocket firmly 100 with the edge of the flap reaching to the curved base of the shank or finger 12.

The wedge 17 is preferably arched in cross section, as plainly shown in Figs. 5 and 6, to provide a desired large bearing surface 105 in the apertured lug 13 and the inner surface of the cap 11, thus preventing the wedge from becoming accidentally dislodged. The forward end of the wedge 17 is pointed to permit ready insertion of the wedge in the 110 aperture 15 of the lug 13.

Having thus described my invention, I

claim as new and desire to secure by Letters Patent:

1. The combination with a tubular shell provided with a transversely extending slit of a clip having a resilient shank, a toe extending integrally and upwardly from the base end of the shank and adapted to rest exteriorly on the shell adjacent the said slit, a lug extending integrally from the base end 10 of the shank in a rearward direction and passing through the said slit, the said toe being struck up from the said lug to provide an aperture in the lug within the shell, and a wedge passing through the said lug aperture and fitting against the interior surface 15 of the shell.
2. A clip for attachment to a tubular member having a transverse slit comprising a resilient shank terminating at its base in

a rearwardly extending integral lug, a toe 20 struck up from the said lug to provide an aperture in the lug, the said toe extending upwardly from the base end of the shank and being adapted to rest on the exterior face of the tubular member, the said lug 25 being adapted to pass through the said slit, and a wedge approximately U-shaped in cross section and being adapted to be driven into the lug aperture and being adapted to engage the inner surface of the tubular 30 member.

In testimony whereof I have signed my name to this specification in the presence of two subscribing witnesses.

MARCUS T. GOLDSMITH.
